APPARATUS FOR SCORING PAPER, CARD-
BOARD, OR LIKE MATERIAL

Alfred Prior, Deptford, London, England

Application October 17, 1932, Serial No. 638,242,
and in Great Britain October 27, 1931

1 Claim. (Cl. 164—60)

This invention is for improvements in apparatus for scoring paper, cardboard or like material, such as is used for example in packing and box making machinery.

5 The object of the invention is to provide means whereby the scoring apparatus may be adjusted to give any desired depth to each separate score to suit the particular work in hand.

Referring to the drawing which shows one 10 way of carrying the invention into effect, a scoring roller 1 provided with circumferential ridges or blades 2 spaced apart the required amount is arranged to co-operate with a pressure roller hereinafter described, and the material to be scored is fed between the two rollers in the usual 15 manner.

The pressure roller is furnished with plain surfaces at the position where the blades on the scoring roller meet the same so that the scoring 20 is effected entirely by the blades, the pressure roller serving only to support the material.

In accordance with the present invention, the 25 portions of the pressure roller, at the points where the blades on the scoring roller are located, are formed by collars 3 which are capable of axial movement along a spindle 4, and the collars are of tapering form so that when they are moved axially, the space between the periphery of a collar and the edge of the corresponding 30 blade on the scoring roller may be increased or decreased, thus enabling the operator to set each collar independently to give the required depth of groove for each particular score.

The spindle 4 which carries the collars is pro- 35

vided with a groove or keyway 5, and the collars are merely fitted in position by set screws 6 which enter the said keyway.

The ends of the grooved spindle carry two 60 parallel collars 7 of exactly the same diameter which run on plain portions of the roller 1 which carries the scoring blades 2, and these parallel collars form gauge rings for setting the two rollers parallel, after which the tapered collars may be adjusted as required.

65 What I claim as my invention and desire to secure by Letters Patent is:—

In apparatus for scoring fibrous material, the combination with a rotatable shaft provided with a plurality of continuous circumferentially extending scoring projections, of a second shaft supported for rotation adjacent to and substantially parallel with said first named shaft, a plurality of annular members supported on said second shaft for rotation therewith and for adjustment axially thereof, said members having conical peripheral portions disposed in spaced relation with corresponding scoring projections to effect scoring of material passing between the shafts, means for retaining said members against axial displacement on said second shaft and in predetermined spaced relation with said projections to control the depth of scoring, and annular gauge rings carried by one of said shafts adjacent the ends thereof and engaging the other 75 shaft to maintain correct spacing between the 80 shafts and between the scoring projections and the cooperating annular members.

ALFRED PRIOR.
